UNITED STATES PATENT OFFICE.

EUGENE P. MAHONY, OF NEW YORK, N. Y.

VERMIN-PROOF COMBINED MATTRESS AND SPRING.

1,371,919.

Specification of Letters Patent. Patented Mar. 15, 1921.

Application filed October 8, 1920. Serial No. 415,594.

To all whom it may concern:

Be it known that I, EUGENE P. MAHONY, a citizen of the United States, residing at New York, in the county of New York and 5 State of New York, have invented certain new and useful Improvements in Vermin-Proof Combined Mattresses and Springs, of which the following is a specification.

This invention relates to bedding and 10 more particularly to mattresses.

The object of the invention is to so construct a sanitary mattress that all possibility of vermin lodging thereon or getting inside thereof is prevented and which may be 15 washed without in anyway injuring it, either by submerging it in water or other cleansing fluid or applying said fluid thereto in any desired manner.

Another object is to so construct the mattress 20 that it will not require the use of a spring and yet will be sufficiently resilient to be thoroughly comfortable.

Another object is to construct a mattress 25 of this character made of rubber of varying resiliency, the members of which are vulcanized together so as to produce a smooth joint to avoid forming harbors for vermin and to render it comfortable to the user.

With these and other objects in view, the 30 invention consists in certain novel features of construction as herinafter shown and described, and then specifically pointed out in the claims, and in the drawings illustrative of the preferred embodiment of the invention.

35 In the accompanying drawing:

Figure 1 represents a perspective view of a mattress constructed in accordance with this invention; and,

40 Fig. 2 is a transverse section thereof.

In the embodiment illustrated the inflatable mattress 1 constituting this invention comprises a rectangular lower section 2 constructed of vulcanized rubber and fabric 45 similar to the casing of a pneumatic tire and of a thickness to render the side and end walls sufficiently stiff to prevent collapse when subjected to the weight of the user and to cause the section to maintain its shape 50 when inflated. This rubberized fabric must also be airtight to provide for the section 2 being inflated in a manner hereinafter described.

This lower section 2 forms a substitute for 55 the woven wire or spiral spring ordinarily used and includes a bottom 3, top 4, end

walls 5 and side walls 6 and is formed by molding to produce a one-piece structure equipped at any suitable point with an inflation valve 7. The advantage procured by 60 having the walls of the lower section of heavy material and those of the upper section soft and flexible is that the upper section which supports the user may be inflated to any desired extent to provide either a 65 hard or a soft bed without altering the shape of the mattress or permitting it to sag.

This section 2 is surmounted by a correspondingly shaped section 8 composed of 70 soft rubber of the same character as the inner tube of a pneumatic tire and which is vulcanized to section 2 along the upper edges of the sides and ends of said section forming a smooth connection so that no 75 shoulders, or indentations will be formed such as would be likely to harbor vermin. The superposed sections 2 and 8 form individual air chambers which are designed to be inflated to withstand any desired pressure, each having a valve as shown at 7 and 9 for connection with a pump or other suitable compressed air source.

A mattress constructed as above described will be thoroughly sanitary in that it can be 85 washed and disinfected whenever necessary either by deflating it or not and it may be entirely submerged in a cleansing fluid without injuriously affecting it. The exterior only of the mattress is subject to infection 90 since no germs can obtain access to the interior.

The lower section 2 is preferably inflated to a pressure of about forty-five or fifty pounds and the upper section may be inflated to suit the wishes of the user and may be rendered either hard or soft according to the degree of inflation. When so inflated a thoroughly comfortable bed is provided without the use of any springs and one 100 which can be readily collapsed for storing or transportation.

The preferred embodiment of the invention is disclosed in the drawings and set forth in the specification, but it will be 105 understood that any modifications within the scope of the claims may be made in the construction without departing from the principle of the invention or sacrificing any of its advantages.

110
What I claim is:

1. A vermin-proof mattress composed of

superposed inflatable sections, the lower being constructed of a vulcanized comparatively hard rubber fabric and adapted to perform the function of a spring and the upper of soft rubber to provide a bed of varying softness.

2. A vermin-proof mattress composed of superposed inflatable sections, the lower being constructed of a vulcanized comparatively hard rubber fabric and the upper of soft rubber, said sections being vulcanized together to form a smooth airtight joint.

3. A vermin-proof mattress composed of a closed, airtight molded lower section with

a soft rubber upper section superposed thereon and vulcanized thereto.

4. A vermin-proof mattress composed of a lower molded hollow rubber section having an inflation valve, the rubber being of sufficient rigidity to avoid collapse under ordinary conditions, and a soft rubber section superposed on said first mentioned section and vulcanized thereto and equipped with an inflation valve.

In testimony whereof, I affix my signature hereto.

EUGENE P. MAHONY.
